BRUSH CONTAINER

Frank Lieberman, Detroit, Mich.

Application January 23, 1947, Serial No. 723,777

1 Claim. (Cl. 206—15.1)

1

This invention relates to paint brush containers, and more particularly to a portable container within which may be stored and carried a plurality of paint brushes.

It is the object of this invention to provide a wire cage supported within said container and adapted to independently support a plurality of spaced brush enclosing pocket members.

It is the further object of this invention to provide a novel brush containing pocket member adapted to vertically carry and support a brush upon the cage within the container.

It is the further object of this invention to provision a brush cleaning fluid within the container or box into which said cage and brush carrying pockets are immersed with the interiors of said pockets in communication with the cleaning fluid.

These and other objects will be seen from the following specification and claim in conjunction with the appended drawings in which:

Fig. 1 is a partially broken away front elevational view of the paint brush container.

Fig. 2 is an elevational section on line 2—2 of Fig. 1.

Fig. 3 is a perspective view of the cage which supports the brush holding pocket members within the container.

Fig. 4 is a front elevational view of one of the brush carrying pocket members.

Fig. 5 is an elevational section thereof on line 5—5 of Fig. 4.

Fig. 6 is a broken away foreshortened plan view thereof on line 6—6 of Fig. 4 illustrating the pocket fastening members.

Fig. 7 is a section on line 7—7 of Fig. 4; and

Fig. 8 is a fragmentary top plan view thereof illustrating its central brush handle receiving opening.

It will be understood that the above drawings illustrate merely a preferable embodiment of the invention, and that other embodiments are contemplated within the scope of the claims hereinafter set out.

Referring to the drawing, Figures 1 and 2, hollow rectangularly shaped container, or box, 11 is suitably sealed to carry therein a brush cleaning liquid 12, and is provided with a pair of inverted U shaped handles 13 pivotally joined thereto at points 14.

The wire cage shown in Fig. 3 is adapted to be removably nested within container 11 and consists of an upper continuous wire beading 15 from which depend the spaced U shaped parallel pocket supporting members 16.

2

A plurality of U shaped compartment forming members 17 are transversely arranged within rectangular beading 15 and extend under the two supports 16. Members 17 have oppositely projecting horizontal members 18 which extend over the top of beading 15 and are suitably secured thereto as by welding to provide compartments 19.

Wedge shaped container 20 has an inner vertical wall 21 and an inwardly converging wall 22.

Said container has a pair of outwardly and downwardly curved ears 23 and 24 at its ends, one of which is mounted upon beading 15 and the other of which is mounted on element 18 forming a part of the innermost U shaped member 17.

There are two additional U shaped members 25 whose upper ends 26 extend out to beading 15 and are suitably secured thereto to thereby provide compartments 27, 28, 29 and 30.

There are also two additional inverted L shaped members 31 which extend up from outer support 16 and whose horizontal outwardly projecting portions 32 are joined to beading 15 to form the additional compartments 33.

It will thus be noted that compartments 33 are narrower than compartments 19 in view of the positioning of container 20 within said cage.

Horizontally arranged reinforcing outer U shaped members 34 are secured at their ends to the two vertically arranged supports 16 and substantially underlie beaded member 15 to provide a retaining enclosure for compartments 19 and 33 to function in the manner herein set out.

Brush retaining pocket members illustrated in Figures 4 through 8 are adapted to be removably nested within compartments 19, 30, and 33 for holding paint brushes therein, as illustrated in the drawing. The larger pocket members to be inserted within compartments 19 will rest upon support 16; however, the smaller pocket members which are narrower in width and shorter in length are removably positioned within compartments 33 and 30 and rest upon horizontal supporting wire member 35 which is welded to the inner walls of members 25 as fully illustrated in Fig. 1.

The cage shown in Fig. 1 has a pair of carrying handles 36 which are hingedly mounted upon the end portion of beading 15 facilitating handling of cage 15—16 and in its removal from and insertion within container 11.

As shown in Fig. 1 the wire cage projects down into container 11 but beading 15 rests upon the top edges thereof for supporting said cage within said container and above the bottom thereof.

The brush retaining and carrying pocket members Figures 4 through 8 consist of the corresponding hollow cover members 37 and 38 which converge and are pivotally joined to each other at their lower ends by rivets 39. Members 37 and 38 form a converging pocket member which has a rectangular opening 40 at its lower end, but whose upper ends and sides are closed by walls 41 and 42.

Rolled snap locking ears 43 project inwardly and oppositely from the inner central portions of top walls 41. Said ears frictionally bear against projections 44 respectively formed on the portion of the opposing cover corresponding to the ear of the other cover.

Cover members 37 and 38 have aligned longitudinal formations 45 which project inwardly for pressure engagement upon the bristles 46 of the paint brush illustrated in Fig. 1 to hold the same in position within pocket 37-38.

Brush handle 47 extends upwardly and loosely projects through central opening 48 Fig. 8 which is formed by the two cutout portions in top walls 41. The brush is thus carried in vertical position with its bristles retained within pockets 37-38 by members 45 so that the lower ends of said bristles 46 are above the opening 48 in the bottom of the pocket.

Cleaning fluid 12 such as turpentine or a substitute cleaning agent in the bottom of container 11, is of sufficient depth that substantially all of the brush bristles will be immersed therein as illustrated in Fig. 1.

This is the ideal way to store a brush; and the latter will be self cleaned as it stands, and will remain soft and flexible ready for its next use.

The heretofore tedious and disagreeable manual method of rubbing and cleaning of brushes, is eliminated, saving valuable time and prolonging the life of the brush.

In operation the brush is simply placed in an open pocket 37-38 which is then snapped closed and locked with the brush bristles held properly in place vertically by members 45, and with its handle extending up through circular opening 48 in said pocket.

The loaded pocket is then inserted within an empty compartment 19, 30, or 33 depending on the size of the pocket. As the brush stands immersed in cleaning fluid the paint will gradually run off, drop through opening 48, in the pocket, through the cage and into the bottom of container 11. Likewise, sand or other particles in the brush bristles will fall into the bottom of said container.

From time to time the entire cage may be removed by handles 36 without removing the brushes and their retaining pockets. The container can be cleaned and flushed out and new cleaning fluid added, after which the wire cage may be reinserted within the container.

While the larger pockets 37-38 rest upon sup-

port 16 it will be noted as in Fig. 1 that the smaller and shorter pockets will rest upon the horizontal wire support 35. Reinforcing side members 34 function further to retain pockets 37-38 in a vertical position within compartments 19 and 33. Particularly with the wire cage removed from box 11, there is a tendency for the pockets to swing outwardly; and this undesirable tipping is prevented by members 34 which cooperatively engage the end walls of said pockets.

Utility compartments 27, 28 and 29 may be used for small brushes as shown in Fig. 2, as well as for other sash tools or implements normally employed in painting operations.

Having described my invention, reference should now be had to the claim which follows for determining the scope thereof.

I claim:

A paint brush enclosing member adapted to be vertically immersed in a cleaning fluid and comprising a pair of hollow downwardly converging openable closure members having opposed inwardly extending side walls with longitudinally registering outer edges and opposed inwardly extending upper end walls with registering outer edges, opposed inwardly projecting ears at the lower ends of said side walls in overlapped engaging relation, rivets interconnecting said ears for hingedly joining said closure members, corresponding inwardly projecting formed portions intermediate the ends of said closure members and arranged towards the lower ends thereof to compressively and retainingly engage the paint brush bristles of a brush within said enclosing member, the lower ends of said closure members being open to provide fluid communication therewith, an upwardly extending inwardly projecting rolled clasp at the outer edge of each end wall upon opposite sides thereof, and an upturned rim at the outer edge of each end wall spaced from the said clasp to be retainingly engaged by an opposing clasp to maintain said closure members in closed position, said upper end walls having registering central openings through which the paint brush handle loosely projects.

FRANK LIEBERMAN.
